TOY RAILWAY SYSTEM

Rudolph J. Jurick, Irvington, N. J.

Application June 1, 1938, Serial No. 211,109

19 Claims. (Cl. 246—72)

This invention relates to toy railway systems and more particularly to systems including an automatically operated bridge which opens to permit passage of a miniature boat thereunder.

5 Toys are associated with children, serving chiefly as a medium of amusement, but the present day tendency is toward the development of toys which are operating models of the familiar machinery and vehicles of everyday commerce 10 and industry. The apparatus disclosed and described herein falls into this classification, possessing inherent novelty to amuse both young and old and sufficiently unique in construction to inspire respect on the part of technical men 15 well acquainted with the simple principles involved. The action of the various units comprising this invention approximates a sequence of actual events with which the average person is familiar, and places complete control of same 20 in his hands. The human desire to control motion by remote means, enlivened by an average amount of imagination, provides a fertile field of acceptance for toys of the type described. Further, the apparatus herein disclosed fills a 25 definite need in the field of model railway building, as those engaged in such activity are ever seeking to add realism to their layout. A novel apparatus, moderately priced, whereby the above mentioned action may be produced, is broadly the 30 object of this invention.

Another object of the invention is to provide, in a system of the class described, novel means whereby proper opening and closing of the tracks is assured, together with a novel electrical circuit 35 whereby the apparatus is caused to function with a minimum possibility of failure.

A further object of the invention is to provide, in combination with a bridge having a movable span, a novel miniature boat system with an associated electrical control circuit whereby the 40 boat is caused to pass through the open bridge span at the proper time.

Still another object of the invention is the provision of an electrical control circuit or circuits 45 whereby the operation of the apparatus, of the class described, is made entirely automatic.

The above, and other objects and advantages of this invention will be apparent from the following specification when taken with the accompanying drawings in which two embodiments of the invention are illustrated. It is to be expressly understood, however, that the drawings are for purposes of illustration and description only, and are not to be construed as defining the

limits of the invention, reference being had for this purpose to the appended claims.

In the drawings wherein like reference characters refer to like parts in the several views:

Fig. 1 is an isometric view showing the various component parts in approximately correct relative position when the span is closed. 5

Fig. 2 is a diagram of the electrical control circuit, showing only a portion of the entire course of tracks. 10

Fig. 3 is a detail isometric view showing the method of rail construction to assure proper closing of the track sections. 15

Fig. 4 is an elevation of a rotating type bridge, with the span in closed position. 15

Fig. 5 is a fragmentary plan view showing detail of gears and contact switch used in connection with the bridge shown in Fig. 4. 20

The present embodiment of this invention comprises a course of tracks for use with toy railway trains and including a plurality of insulated track sections, a bridge inserted in the course of tracks and including a movable span closing a gap in the course of tracks when in closed position, a toy boat adapted to be moved through the gap when said span is in open position and a signal located at the approach to the bridge, for indicating safe and unsafe conditions, namely, whether the bridge is open or closed. Actuating means are provided for moving the span to and from open position in a continuous operation and for simultaneously moving the boat through the gap when the span is in open position. Means are also provided for operating the train signal and for stopping the boat at a predetermined point. These actuating means are in turn initiated by the train upon reaching an insulated section in the track course. 30

The apparatus as shown in Fig. 1 comprises a bridge structure mounted on a suitable mounting board 1, with fixed spans 8 and 9 and movable span 10, the latter fulcrumed by and free to rotate about shaft 11 which is in turn secured to the mounting board by angle pieces 12. Shaft 13, to which are fastened cams 14 by screws 15 is driven by motor 16, being directly coupled thereto by pin 17 or any other suitable means. Cams 14 operate against the floor of movable span 10, their shape being such that as shaft 13 is rotated by motor 16, span 10 opens and closes for each revolution of said cams. The continuous motion of span 10, from a closed to open, and back to closed position, accomplished by use of unidirectional motor 16 is one of the novel fea- 40

45

50

55

55

tures of this invention, reducing the cost and adding to the simplicity of the apparatus.

The train, shown diagrammatically in dotted lines at 10a in Fig. 2, may be of the conventional 5 electric toy type used in toy railway systems, and is energized by current flowing in the tracks in the usual manner well known to those skilled in the art, the current being supplied from the usual 110 volt source through the transformer 38 10 connected to the tracks at 39.

Novel means are provided for operating the boat in the manner hereinbefore described and, in the form shown, said boat operating means comprise pulleys 18 and 19 of suitable construction, connected by endless belt 20, having miniature boat 21 secured thereto. By means of a drive fit or equivalent, pulley 18 is secured to shaft 22, said shaft being coupled to motor 23 by pin 24, and free to rotate in angle pieces 25. 20 Pulley 19 is free to rotate about shaft 26, said shaft being in turn free to rotate in angle pieces 27 and held in position by pins 28. Motor 23 rotates the pulley and belt system causing boat 21 to move linearly along the path defined by belt 28, said boat being exposed to view while traveling along the upper portion of the belt and hidden from view by mounting board 7 when returning to its original starting position.

In order to prevent the boat from passing 30 through the bridge when the movable span is closed or not open sufficiently, it is desirable to have the boat stop at the same point after each cycle of operation. In the present instance this is accomplished by a contact switch included in 35 the electrical circuit and operated by the bridge actuating means. As illustrated in Fig. 1 the contact switch comprises the switch 34 mounted on board 7 in a suitable manner and in such position as to cooperate with a pin 35 which is rigidly 40 secured to shaft 13. Pin 35 causes said switch to open and close at the correct time in the cycle of operation, thereby causing boat 21 to stop at a predetermined point as more fully explained hereinafter.

45 A novel method of constructing the joining ends of adjacent track sections is also provided and comprises cutting away part of the tubular section of one rail and providing a pin in the tubular section of the adjoining rail so that said 50 pin engages the cut away portion of the first rail when the span is in closed position. Fig. 3 discloses one form of the above mentioned method as applied to the ends of rails 29, 30, 31. The method, in the present instance, is carried out by 55 cutting away the upper portion of rails 30 to accommodate pins 32 provided in the ends of rails 29. Thus as span 10 is lowered into closed position, the two track sections properly engage, both electrically and mechanically, even though span 60 18 possesses a certain amount of play along shaft 11. The adjoining ends of rails 29 and 31 are constructed in a similar manner, wire jumpers 33, Fig. 1, providing a good electrical contact between these two track sections at all times.

65 The cycle of operation for the entire apparatus, with particular reference to Fig. 1 and Fig. 2, is as follows.

In the normal or starting position, i. e., just before the train 10a reaches track section B from 70 the right as viewed in Figs. 1 and 2, the span 10 is closed, motors 16 and 23 are de-energized, switch 34 is held open by pin 35, boat 21 is hidden from view by mounting board 7, and relays 36 and 37 are in de-energized or open position.

75 With relay 36 open, current is supplied to in-

sulated track section A, from transformer 38, to the course of tracks at points 39, through the tracks 40 of the closed span, wire 41, contacts 42 and 43 and wire 44. Insulation of the various track sections is accomplished by conventional 5 pin type insulators 45. It should be noted that the center rail circuit is unbroken except when span 10 is in opened position, electrical control being achieved by insulating proper sections of the outside rails, which for purposes of clarity 10 are shown as the conventional type wherein both outside rails are tied together electrically. With relay 37 open, contacts 46 and 47 of this relay complete the circuit to the green lamp of train signal 48 through wires 49 and 50, indicating that 15 the track across the bridge is clear.

All units remain in the normal position as explained above as long as master control switch 51 is open, under which condition the train would continue its course over the tracks, uninterrupted. To initiate the automatic operation of the apparatus it is only necessary to close master control switch 51 either manually or automatically by means of a time clock, time delay relay, etc.

With switch 51 closed, the passage of the train 10a over insulated track section B causes this section to become alive due to the spanning of the outside track insulator pins 45 by the wheels of the various cars. This energizes rectifier 52 30 through wires 53, which in turn energizes relay 36, the coil of said relay being permanently connected across the output side of the rectifier. It can be seen that the substitution of a low voltage, alternating current relay for relay 36 eliminates 35 the need for rectifier 52. The instant relay 36 closes, it locks itself in electrically, current for this purpose being supplied through wires 41 and 53, and contacts 43 and 54. Also, the opening of contacts 42 and 43 removes the current from 40 the outside rails of insulated track section A, said insulated section being long enough to accommodate the entire train 10a with sufficient allowance to permit the train to coast to a stop 45 on this section. Thus, the train 10a comes to a stop on track section A, as shown diagrammatically in dotted lines in Fig. 2, but it should be noted that the remainder of the endless track course remains energized thereby making it possible to operate other train accessories from any 50 other section of the track course. A second set of contacts, 55 and 58, on relay 36, energize relay 37 and complete the 110 volt power circuit to 55 motors 16 and 23 causing them to rotate the shafts attached respectively thereto. Contacts 47 and 56 of relay 37 change the light in signal 48 from green to red by shifting the circuit from wires 49 and 50 to wires 50 and 57. In systems 60 where a signal is not desired, relay 37 is dispensed with.

65 Motor 16 rotates shaft 13 causing pin 35 to allow the contacts of switch 34 to close and cams 14 to raise span 10. Motor 23 rotates pulley 18 which causes boat 21 to move with belt 20. Both motors are small, clock type, having built 70 in gear reductions and their shaft speeds are so chosen that when used in conjunction with a predetermined length of belt 20, and predetermined diameter of pulleys 18 and 19, boat 21 will always pass through the bridge when 75 span 10 is opened to approximately the maximum height. The initial starting position of boat 21 is predetermined for any particular combination of shaft speeds, belt length and pulley diameter. Switch 34 serves to stop the boat at the same 75

point at the termination of each cycle of operation, as more fully explained hereinafter.

The electrical circuit is so designed that when rails 29 disengage from rails 30 as span 10 opens, current is removed from the coil of relay 36, said relay thereupon returning to its normal or open position. However, by this time in the cycle the contacts of switch 34 are closed, said contacts being in parallel electrical connection with contacts 55 and 58 of relay 36 and therefore motors 16 and 23 continue to rotate and relay 37 remains closed.

The return of relay 36 to normal position does not supply current to insulated track section A, (upon which the train 10a is now resting) because of the open circuit existing between rails 29 and 30, power to the track course being supplied at points 39. Thus, span 10 continues through the opening and closing cycle and boat 21 continues around pulley 19. As span 10 reaches the closed position, the engagement of rails 29 and 30 completes the electrical circuit to insulated track section A, through wires 41 and 44 and contacts 42 and 43 of relay 36, causing the train 10a to start on its course over the bridge, to the left as viewed in Figs. 1 and 2. Motors 16 and 23, however, continue to rotate until pin 35 opens the contacts of switch 34, the opening of said switch 34 removing the current from motors 16 and 23, and the coil of relay 37. Motors 16 and 23 thereupon stop immediately and relay 37 returns to normal or open position. Contacts 46 and 47 of relay 37 change the light in signal 48 from red to green by shifting the circuit from wires 50 and 57 back to wires 49 and 50. The time differential between the instant when the train 10a starts and the signal changes from red to green depends upon the location of pin 35 relative to cams 14. This difference may be reduced to an inconsequential value by proper adjustment of the parts involved, being entirely removed in systems operating without a signal.

From the foregoing it will be seen that switch 34 serves to definitely stop boat 21 at approximately the same point at the end of each cycle of operation, and therefore precludes the possibility of said boat from passing through the bridge except when span 10 is properly opened. It will also be seen that by doubling the length of belt 20 or halving the speed of shaft 22, two miniature boats may be attached to belt 20, said boats alternately passing through the bridge.

Another embodiment of this invention is disclosed in Fig. 4 and Fig. 5. Unidirectional motor 59 has securely attached thereto gear 60, said gear having the teeth of opposite quadrants removed, substantially as shown. Gear 65 is securely attached to shaft 66, said shaft being permanently affixed to movable bridge span 67, in any suitable manner. Collar 68 secured to shaft 66 by screw 69 serves to support the movable span 67 on mounting board 7. Pin 70 protruding from the face of gear 60, engages the extended blade of switch 34 and causes the contacts of said switch to open and close at the proper time in the operating cycle.

Motor 59 rotates gear 60 in the direction shown and quadrant 62 of said gear causes gear 65 to rotate through an angle of 90 degrees, thereby opening span 67 to a position at right angles to fixed spans 71. Movable span 67 remains in this position as quadrant 61 of gear 60 passes by the point of mutual contact between the two gears thus allowing sufficient time for boat 21

(Fig. 1) to pass through the bridge. As gear 60 continues to rotate, quadrant 64 again engages the teeth of gear 65 causing movable span 67 to rotate another 90 angular degrees thereby returning to the closed position. As quadrant 63 of gear 60 passes by gear 65, pin 70 causes the contacts of switch 34 to open; said contacts serving the same purpose in this embodiment as described in the early part of this specification. The ineffective quadrant 63 of gear 60 permits a wide latitude in the location of switch 34 on mounting board 7.

Although only two embodiments of the invention have been illustrated and described, various changes in form, construction and relative arrangement of parts, which will now be apparent to those skilled in the art, may be made without departing from the scope of the invention. Reference is therefore to be had to the appended claims for a definition of the limits of the invention.

What is claimed is:

1. A top railway system having a course of tracks for use with toy railway trains and including a plurality of insulated track sections, a bridge inserted in the course of tracks and comprising a movable span closing a gap in said course of tracks when in closed position, a toy boat adapted to be moved through the gap when said span is in open position, a signal located at the approach to the bridge for indicating safe and unsafe conditions, actuating means for moving the span to and from open position in a continuous operation and for simultaneously moving the boat through the gap when the span is in open position and for cutting off the power from one of the insulated track sections and for operating the signal; said actuating means being initiated by the train upon reaching another of said insulated sections of track, and means for stopping the boat at a predetermined point.

2. A toy railway system having a course of tracks for use with toy railway trains and including a plurality of insulated track sections, a bridge inserted in the course of tracks and comprising a movable span closing a gap in the said course of tracks when in closed position, a toy boat adapted to be moved through the gap when the span is in open position, a signal located at the approach to the bridge for indicating safe and unsafe conditions, actuating means for moving the span to and from open position and for simultaneously moving the boat through the gap when the span is in open position and for cutting off the power from one of the insulated sections of track and for operating the signal; said actuating means being initiated by the train upon reaching another of said insulated sections of track, and means for stopping the boat at a predetermined point.

3. A toy system comprising, in combination, a toy bridge having a movable span closing a gap in the bridge when in closed position, a toy boat adapted to be moved through the gap when said span is in open position, a signal located at the approach to the bridge, actuating means for moving the span to and from open position, actuating means for simultaneously moving the boat through the gap when said span is open, means for operating the signal, common means for simultaneously controlling the operation of all of said means, and means controlled by said span actuating means for stopping the boat at a predetermined point.

4. A toy system comprising, in combination, a

- toy bridge having a movable span closing a gap in the bridge when in closed position, a toy boat adapted to be moved through the gap when said span is open, a signal located at the approach to the bridge for indicating safe and unsafe conditions, actuating means for moving the span to and from open position, actuating means for simultaneously moving the boat through the gap when said span is open, means for operating the signal to give one indication when the span is open and another indication when the span is closed, and common means for simultaneously controlling the operation of all of said means.
5. A toy system comprising, in combination, a toy bridge having a movable span closing a gap in the bridge when in closed position, a toy boat adapted to be moved through the gap when said span is in open position, actuating means for moving the span to and from open position, actuating means for simultaneously moving the boat through the gap, common means for controlling the operation of all of said means, and means controlled by said span actuating means for stopping the boat at a predetermined point.
10. 6. A toy system comprising, in combination, a toy cantilever bridge having a movable span closing a gap in the bridge when in closed position, a toy boat adapted to be moved through the gap when said span is open, actuating means for moving the said span to and from open position, actuating means for simultaneously moving the boat through the gap, and common means for simultaneously controlling the operation of both of said actuating means.
15. 7. A toy system comprising, in combination, a toy rotary bridge having a movable span closing a gap in the bridge when in closed position, a toy boat adapted to be moved through the gap when said span is in open position, actuating means for rotating the span to and from open position, actuating means for simultaneously moving the boat through the gap when said span is open, and common means for simultaneously controlling the operation of both of said actuating means.
20. 8. A toy railway system having a course of tracks for use with toy railway trains and including a plurality of insulated sections of track, a bridge inserted in the course of tracks and comprising a movable span closing a gap in the course of tracks when in closed position, a toy boat adapted to be moved through the gap when said span is in open position, and actuating means for cutting off the power from one of the insulated sections of track, for moving the span to and from open position and for simultaneously moving the boat through the gap when said span is open, said actuating means being initiated by the passage of the train over another of said insulated sections of track.
25. 9. A toy railway system having a course of tracks for use with toy railway trains and including a plurality of insulated sections of track, a bridge inserted in the course of tracks and comprising a movable span closing a gap in the course of said tracks when in closed position, and actuating means initiated by the train upon reaching one of the insulated sections of track, for cutting off the power to another of said insulated sections of track and for moving the span to and from open position.
30. 10. A toy railway system having a course of tracks for use with toy railway trains, a bridge inserted in the course of tracks and comprising a movable span closing a gap in the course of

tracks when in closed position, a toy boat adapted to be moved through the gap when said span is in open position, a signal located at the approach to the bridge, actuating means for moving the span to and from open position and for simultaneously moving the boat through the gap when said span is open, actuating means for operating the signal to give one indication when said span is open and effective upon closing of the span to give a different indication, means operated by the train in approaching the bridge to initiate the operation of both of said actuating means, and means for stopping the boat at a predetermined point.

11. A toy railway system having a course of tracks for use with toy railway trains, a bridge inserted in the course of tracks and comprising a movable span closing a gap in the course of said tracks when in closed position, a toy boat adapted to be moved through the gap when the span is in open position, actuating means for moving the span to and from open position and for simultaneously moving the boat through the gap when the span is open, means operated by the train in approaching the bridge for initiating the operation of said actuating means, and means for stopping the boat at a predetermined point.

12. A toy railway system having a course of tracks for use with toy railway trains, a bridge inserted in the course of tracks and comprising a movable span closing a gap in the course of tracks when in closed position, a toy boat adapted to be moved through the gap when said span is in open position, actuating means for moving the span to and from open position and for simultaneously moving the boat through the gap when said span is open, means operated by the train in approaching the bridge for initiating the operation of the actuating means, and means for stopping the train when the operation of the actuating means is initiated.

13. A toy railway system having a course of tracks for use with toy railway trains, a toy train movable on said tracks, a toy cantilever bridge inserted in the course of tracks and comprising a movable span closing a gap in the course of tracks when in closed position, a toy boat adapted to be moved through the gap when said span is open, and actuating means controlled by said train upon approaching said span for moving the span to and from open position and for simultaneously moving the boat through the gap when said span is in open position.

14. A toy railway system having a course of tracks for use with toy railway trains, a toy train movable on said tracks, a toy rotary bridge inserted in the course of tracks and comprising a movable span closing a gap in the course of tracks when in closed position, a toy boat adapted to be moved through the gap when said span is in open position, and actuating means controlled by said train upon approaching said span for rotating the span to and from open position and for simultaneously moving the boat through the gap when the span is in open position.

15. A toy railway system having a course of tracks for use with toy railway trains, a toy train movable on said tracks, a toy bridge inserted in the course of tracks and comprising a movable span closing a gap in the course of tracks when in closed position, a toy boat adapted to be moved through the gap when said span is open, and actuating means controlled by said train upon approaching said span for moving the span to and from open position and for simultaneously

moving the boat through the gap when the span is in open position.

16. A toy system comprising, in combination, a toy bridge having a movable span closing a gap in the bridge when in closed position, a toy boat adapted to be moved through the gap when said span is in open position, and actuating means controlled from a point external of and removed from said bridge and boat for moving the span to and from open position and for simultaneously moving the boat through the gap when the span is in open position.

17. A toy railway system having a course of tubular tracks for use with toy railway trains, a toy train movable on said tracks, a toy bridge inserted in the course of tracks and comprising a movable span having a section of tubular tracks closing a gap in the course of tracks when in closed position, the ends of the tracks of the span and the ends of the tracks with which the tracks of the span join being so constructed that the ends of one are partially cut away longitudinally and the ends of the other are provided with pins or rods which fit the partially cut away portions to properly close the course of tracks at the span, a toy boat adapted to be moved through the gap when said span is open, and actuating means controlled by the train upon approaching said span for moving the span to and from open position and for simultaneously moving the boat through the gap when said span is in open position.

18. A toy railway system having a course of tubular tracks for use with toy railway trains, a toy train movable on said tracks, a toy bridge inserted in the course of tracks and comprising a movable span having a section of tubular tracks closing a gap in the course of tracks when in closed position, the ends of the tracks of the span and the ends of the tracks with which the tracks of the span join being so constructed that the ends of one are partially cut away longitudi-

nally and the ends of the other are provided with pins or rods which fit the partially cut away portions to properly close the course of tracks at the span, a toy boat adapted to be moved through the gap when said span is open, actuating means controlled by the train upon approaching said span for moving the span to and from open position and for simultaneously moving the boat through the gap when said span is in open position, and means for stopping the boat at a predetermined point of travel after it has passed through the gap and the span is closed.

19. A toy railway system having a course of tubular tracks for use with toy railway trains, a toy train movable on said tracks, a toy bridge inserted in the course of tracks and comprising a movable span having a section of tubular tracks closing a gap in the course of tracks when in closed position, the ends of the tracks of the span and the ends of the tracks with which the tracks of the span join being so constructed that the ends of one are partially cut away longitudinally and the ends of the other are provided with pins or rods which fit the partially cut away portions to properly close the course of tracks at the span, a toy boat adapted to be moved through the gap when said span is open, actuating means controlled by the train upon approaching said span for moving the span to and from open position and for simultaneously moving the boat through the gap when said span is in open position, means for stopping the boat at a predetermined point of travel after it has passed through the gap and the span is closed, and a signal device at the approach to said bridge and controlled by the train upon approaching said bridge to give one kind of an indication and controlled by the actuating means upon closing of the span to give another kind of indication.

RUDOLPH J. JURICK. 40
